CLAIM

The ornamental design for a front fork triple clamp assembly, as shown and described.

DESCRIPTION

FIG. 1 is a top perspective view showing the top, front, and left sides of a front fork triple clamp assembly in one intended environment;

FIG. 2 is a top view showing the top, front, and left sides of the front fork triple clamp assembly;

FIG. 3 is a bottom perspective view showing the bottom, rear, and right sides of the front fork triple clamp assembly;

FIG. 4 is a front elevation view of the front fork triple clamp assembly;

FIG. 5 is a rear elevation view of the front fork triple clamp assembly;

FIG. 6 is a left side elevation view of the front fork triple clamp assembly;

FIG. 7 is a right side elevation view of the front fork triple clamp assembly;

FIG. 8 is a top plan view of the front fork triple clamp assembly; and,

FIG. 9 is a bottom plan view of the front fork triple clamp assembly.

The broken lines in the drawing depict portions of the front fork triple clamp assembly and environment that form no part of the claimed design.
